UNITED STATES PATENT OFFICE.

STEPHEN S. NEWTON, OF BINGHAMTON, NEW YORK.

BOTTLE-STOPPER.

SPECIFICATION forming part of Letters Patent No. 279,419, dated June 12, 1883.

Application filed April 20, 1882. (No model.)

To all whom it may concern:

Be it known that I, STEPHEN S. NEWTON, a citizen of the United States, residing at Binghamton, in the county of Broome and State of New York, have invented certain new and useful Improvements in Bottle-Stoppers, of which the following is a specification, reference being had therein to the accompanying drawings.

10 Figure 1 is an elevation, partly in section, of a bottle-stopper containing my invention, with the ports open; and Fig. 2 is a similar view with the ports closed.

In the drawings, A is a cylindrical discharge-tube, provided near its upper end with a port, a.

B is an expanded head, provided with a flaring portion, b, and a lower screw-threaded part or shank, k, which screws into the upper end of the discharge-tube.

C is a cylinder surrounding and fitting closely the upper portion of the discharge-tube, and provided at its upper end with a flaring flange, D, adapted to fit closely the part b.

25 H h is a flange projecting from the lower end of cylinder C, the part h being parallel with the lower end of the discharge-tube.

I is a flange projecting horizontally from the discharge-tube, and adapted to cover a tube-30 cork to be applied to the screw-threaded portion J of the discharge-tube.

i is a collar projecting upwardly from the flange I, and within the part h.

E is a spiral spring surrounding the discharge-tube and within the collar i, its upper end engaging with the under side of flange H, and serving to thrust cylinder C and flange D up against the part b of the head, and thus close the discharge-port a, which may be readily opened by pressing the cylinder and flange

down into the position shown in the drawings.

It will be seen that the flange h and collar i overlap each other, and thus screen the spiral spring E from observation.

Attaching the head D and the discharge-tube by means of a screw-threaded shank, k, facilitates the application of the cylinder C and spring E to the discharge-tube A and their removal therefrom.

What I claim is—

1. In a bottle-stopper, the combination of the discharge-tube A, having port a, the head B, sliding cylinder C, and spring E, the head B being provided with the threaded shank k, engaging with the threaded upper portion of tube A, substantially as set forth.

2. In a bottle-stopper, the combination, with the discharge-tube A, having port a, a flange, I, and a screw-thread, J, of the sliding cylinder C, provided with flange H h, and the spring E, 60 interposed between flanges I H, substantially as set forth.

3. In a bottle-stopper, the combination, with the discharge-tube A, having port a, of the head B b, sliding cylinder C, having flange D, 65 and the spring E, operating to thrust the cylinder C and flange D upward, substantially as set forth.

4. In a bottle-stopper, the discharge-tube A, having port a, and the flange I, made integral with the tube, the head B, detachably secured to the discharge-tube, the sliding cylinder C, and spring E, substantially as set forth.

In testimony whereof I affix my signature in presence of two witnesses.

STEPHEN SILSSEE NEWTON.
